ATTORNEY

UNITED STATES PATENT OFFICE.

ALFRED V. HOENER, OF EAST PITTSBURGH, PENNSYLVANIA.

RAIL-JOINT.

1,118,771.

Specification of Letters Patent.

Patented Nov. 24, 1914.

Application filed May 6, 1914. Serial No. 836,754.

To all whom it may concern:

Be it known that I, ALFRED V. HOENER, a citizen of the United States of America, residing at East Pittsburgh, in the county of Allegheny and State of Pennsylvania, have invented certain new and useful Improvements in Rail-Joints, of which the following is a specification, reference being had therein to the accompanying drawing.

10 This invention relates to rail joints and has for its object to provide a device of such class, in a manner as hereinafter set forth, for connecting a pair of track rails together without the employment of nuts and bolts, 15 at the same time allowing for the necessary contraction and expansion of the track rails due to climatic conditions.

Further objects of the invention are to provide a rail joint or clamp which is simple 20 in its construction and arrangement, readily applied, efficient and convenient in its use, strong, durable and inexpensive to manufacture.

With the foregoing and other objects in view, the invention consists of a novel construction, combination and arrangement of parts as hereinafter more specifically described and illustrated in the accompanying drawings, wherein is shown an embodiment 30 of the invention, but it is to be understood that changes, variations and modifications can be resorted to which come within the scope of the claims hereunto appended.

In the drawings wherein like reference 35 characters denote corresponding parts throughout the several views:—Figure 1 is a side elevation of a rail joint in accordance with this invention. Fig. 2 is a cross sectional view of a track rail showing the 40 adaptation therewith of a rail joint in accordance with this invention. Fig. 3 is a perspective view of one of the clamping arms. Fig. 4 is a perspective view of the other clamping arm, and Fig. 5 is a perspective view broken away of the end of the 45 tool employed for separating the clamp arms.

Referring to the drawings in detail, 6 and 7 denote a pair of track rails each of 50 which has its web 8 provided with an opening 9. The track rails 6—7 are mounted upon and suitably secured to a tie 10, and arranged at each side of the track rails is a fish plate 11, which abuts against the 55 heads 12 and bases 13 of said rails. The fish plates 11 are provided with openings 14

which register with the openings 9, and extending through said registering openings are cylindrical bars 15 having each end provided with a reduce cylindrical stem 16. 60 The stem 16 projects outwardly from the fish plates 11.

The fish plates 11 are clamped to the track rails through the medium of a plurality of pairs of inter-engaging clamping 65 arms, the number of pairs of clamping arms depending upon the number of bars 15 employed. Preferably but two bars 15 are employed, under which conditions two pairs of inter-engaging clamping arms are employed. 70 The clamping arms of each pair are indicated by the reference characters 17—18 and each of said arms is provided with a base 19 which at its outer terminus merges into a round extension 20, the latter 75 having projecting therefrom an upwardly and inwardly extending groove arm 21. The arm 21 has the upper terminus of its inner face formed with a rectangular offset 22 formed with a centrally disposed pocket 80 23, into which projects a stem 16. The bases 19 of the arms 17—18 are positioned against the lower face of the bases 13 of the track rails and the said bases 19 of said arms 17—18 are oppositely disposed with respect 85 to each other, but extend in the same plane.

The base 19 of the arm 17 has its lower face serrated to provide transverse teeth 24. The free terminus of the base 19 of the arm 17 is beveled as at 25, and projecting from 90 said beveled terminus 25 is the downwardly inclined inner portion 26 of a locking arm 27, the latter when the arms 17—18 are in clamping position, engages the lower face of the base 19 of the arm 18. The inclined 95 portion 26 of the locking arm 27 is disposed centrally with respect to the beveled terminus 25.

The free terminus of the base 19 of the arm 18 is beveled as at 28, the bevel being 100 opposite with respect to the bevel of the free terminus of the base 19 of the arm 17, and formed integral with the base 19 of the arm 18, at the free terminus of said base, is the downwardly inclined portion 29 of a pair 105 of locking arms 30. The arms 30 are flush with the sides of the base 19 of the arm 18 and are spaced from each other. The top edge of each of the arms 30 is provided with teeth 31 adapted to engage in the teeth 24 110 when the arms 17—18 are arranged in clamping position. The free end of each

of the arms 30 at the top edge thereof, is 5 cut away as at 32 to provide a shoulder which opposes the base 19 of the arm 17 and forms in connection with said base a recess 33, into which is adapted to extend a lug 34 carried by a tool 35 whereby the arms 30 can be pried away from the base 19 of the arm 17 whereby the clamping arms can 10 be disconnected from each other and the fish plates 11 released.

When the arms of each pair of clamping arms are in operative position, the inclined portion 26 extends outwardly between the arms 30, and the arm 27 is positioned against the base 19 of the arm 18, and the arms 30 are positioned below the base 19 of the arm 17, but the teeth 31 of said arms 30 engage in the teeth 24 formed on the lower face of the base 19 of the arm 17, and when 20 the arms 27 and 30 are in the position as stated, the arms 17—18 are maintained in clamping engagement with the offset portion 22 bearing against the fish plates 11 and the pocket 23 receiving the stem 16. 25 The arms 17—18 are resilient whereby they will snap in position.

Although the clamp is shown employed in connection with the rail joint, yet, it is to be understood that the clamp can be 30 adapted for any purpose wherein it is found applicable.

What I claim is:—

1. The combination of a bar having a stem at each end, of a pair of clamping arms 35 having the inner face thereof at the top formed with a flat bearing surface provided with a recess for the reception of a stem, said surface bearing against said bar, each of said arms including a base, said bases being oppositely disposed and extending in 40 the same plane with respect to each other, one of said bases having its lower face provided with teeth, a locking arm projecting from said toothed base and adapted to engage the lower face of the other base, and a pair of locking arms projecting from the 45 smooth base and provided with teeth adapted to engage in said toothed base, said pair of locking arms having said single locking 50 arm extending therebetween.

2. In combination a pair of rails, a pair of fish plates positioned against the sides of said rails, bars extending through said rails and fish plates and having their ends

provided with stems, clamping arms abutting against the fish plates and receiving said stems and further abutting against the lower face of the bases of said rails, one of said arms having projecting therefrom a locking arm engaging the other of said 60 clamping arms, said last mentioned clamping arm provided with a pair of locking arms through which extends the first mentioned locking arm, said pair of locking arms provided with teeth engaging in the 65 first mentioned clamping arm.

3. A clamp comprising a bar adapted to extend through the elements to be clamped together, said bar having each of its ends provided with a stem, a pair of members 70 abutting against the ends of said bar and having pockets for the reception of said stems, each of said members provided with a base, said bases arranged in the same plane and extending in opposite directions with 75 respect to each other, one of said bases being toothed and provided with an arm engaging the other of said base, said last mentioned base provided with a pair of arms having teeth engaging in the first mentioned 80 base, said arms when engaging said base maintaining said members in clamping position.

4. A clamp comprising a bar adapted to extend through the elements to be clamped 85 together, said bar having each of its ends provided with a stem, a pair of members abutting against the ends of said bar and having pockets for the reception of said stems, each of said members provided with 90 a base, said bases arranged in the same plane and extending in opposite directions with respect to each other, one of said bases being toothed and provided with an arm engaging the other of said base, said last mentioned base provided with a pair of arms having teeth engaging in the first mentioned base, said arms when engaging said base maintaining said members in clamping position, said single arm extending between 100 said pair of arms.

In testimony whereof I affix my signature in the presence of two witnesses.

ALFRED V. HOENER.
